AUTOMOBILE SPRING CONSTRUCTION

Robert J. Proske, St. Louis, Mo., assignor to
Virginia Ruth Proske, St. Louis, Mo.

Application May 3, 1952, Serial No. 285,898

4 Claims. (Cl. 267—28)

1

Generally, the present invention relates to a compound spring construction for use on automotive vehicles to minimize the shocks incident to road travel.

More particularly, the invention is directed to an improved spring construction for incorporation in the chassis of a standard automobile, without requiring any changes in the present design of said chassis.

The primary object of the invention is to provide a novel spring construction which not only includes the normal inherent shock-absorbing characteristics of conventional spring assemblies, but which provides additional resiliency substantially centrally of the assembly.

Another object is to provide an improved assembly which embodies a semi-elliptic leaf spring, a quarter-elliptic leaf spring and a compression coil spring, so arranged and complementarily disposed as to effectively neutralize and absorb road shocks, and to prevent the transmission of them to the body of the vehicle to which the assembly is applied.

A further object of the invention is to provide a resilient connection between the forward end of said semi-elliptic spring and a portion of said quarter-elliptic spring intermediate the forward and rear ends of the latter, said connection comprising hanger linkage including bushings of resilient material such as rubber or neoprene, as will appear.

Another object of the invention is to provide an included semi-elliptic leaf spring one half of which is normally horizontally disposed, the other half being of a generally quarter-elliptic contour.

A more comprehensive understanding of my invention may be had from the detailed description thereof to follow with reference to the accompanying drawing, wherein the invention is illustrated in its normal, or inactive status.

In said drawing:

Figure 1 is a view in top plan of a spring construction incorporating the present invention;

Figure 2 is a side elevational view thereof;

Figure 3 is a bottom plan view thereof;

Figure 4 is an enlarged vertical sectional view taken on the line 4—4 of Figure 2;

Figure 5 is a similar view taken on the line 5—5 of Figure 2; and

Figure 6 is also an enlarged vertical sectional view taken on the line 6—6 of Figure 2.

In Figures 1 through 3, the spring construction comprising the present invention is designated as a whole by the numeral 10. Included are an upper leaf spring generally designated

2

by numeral 12; a lower leaf spring indicated 14; linkage designated 16 for connecting the front end of the upper spring with a portion of the lower spring adjacent the front end of the latter; a coil compression spring assembly generally designated 18; and related parts and elements as will appear hereinafter.

The upper leaf spring 12 is contoured as shown, and includes a normally horizontal section 20, 10 an arcuate or quarter-elliptic section 22, front eye 24, and a rear eye 26.

The lower spring 14 is quarter-elliptic as illustrated, and terminates at its front end in an eye 28. Said spring is further provided with a second eye 30 in vertical alignment with the eye 24 of the upper spring 12.

As seen to best advantage in Figure 5, the linkage 16 includes a first link 32; a pair of laterally projecting pins 34 and 35 integral therewith; a second link 36 provided with apertures 38 through which said pins project; a bushing 40 of resilient material interposed in eye 24 about the upper pin 34; a similar bushing 42 interposed in eye 30 about the lower pin 35; and a pair of nuts 43, one of which engages the threaded extremity of pin 34, the other engaging the threaded extremity of pin 35.

The rear end section 46 of spring 14 is disposed beneath a conventional axle housing 48, the latter being provided with integral lateral flanges 50, apertured for the reception of the leg members of a pair of U-bolts 52.

The assembly 18 includes an upper circular plate 54 disposed below the forward end portion of the horizontal spring section 20; a headed bolt 56 passing through aligned apertures in said spring section and a central aperture 57 in said plate; a nut 58 engaging the projecting lower extremity of said bolt; a lower non-circular plate 60; a headed bolt 62 passing through aligned apertures in the rear end section 46 of spring 14 and an aperture 64 in the forward segment 66 of said lower plate; a nut 67 engaging the projecting lower extremity of bolt 62; and a coil compression spring 68 interposed between the upper plate 54 and the rear segment 70 of the lower plate 60.

As suggested at 72, the upper and lowermost coils of spring 68 are welded respectively to the plate 54 and the plate 60, and as shown at 74 in Figure 6, the axle housing 48 is recessed to accommodate the head of bolt 62.

The forward segment 66 of the lower plate is further apertured for the passage therethrough of the legs of U-bolts 52, the extremities of which are engaged by nuts 76.

From the foregoing description augmented by an inspection of the drawing, it should be apparent that this invention provides a novel combination of spring structures adapted to attain its objectives.

By means of the front eye 28 and rear eye 26, the assembly 10 may be conveniently mounted on any standard automobile chassis, it being obvious that the distance obtaining between said eyes may be varied to suit chassis requirements, as should be understood.

The novel contour of upper spring 12, the inherent resiliency of linkage 16, and the cushioning effectiveness of compression spring 68 combine to provide a mutually complementary spring construction for preventing the transmittal of road shock to the body of an automotive vehicle.

It is to be understood that whereas the drawing illustrates, and the foregoing description sets forth the preferable embodiment thereof, my invention contemplates all modifications in design, and any equivalents which may fall within the scope of the appended claims.

What I claim is:

1. A spring construction of the character described, including an upper semi-elliptic leaf spring and means integral therewith for mounting the rear end thereof on a chassis; a quarter-elliptic lower leaf spring and means integral therewith for mounting the forward end thereof on said chassis; resilient linkage connecting the forward end portions of said upper and lower springs; a non-circular plate, means for connecting the rear end of the lower spring to an axle housing and simultaneously supporting said non-circular plate therebeneath; and a coil compression spring interposed between said upper spring and the non-circular plate aforesaid for augmenting the inherent resiliency obtaining between the upper and lower springs aforesaid.

2. A spring construction of the character described, including an upper semi-elliptic leaf spring and means integral therewith for mounting the rear end thereof on a chassis, said spring including a normally horizontal rear section merging into a quarter-elliptic forward section; a quarter-elliptic lower leaf spring and means integral therewith for mounting the forward end thereof on said chassis; resilient linkage connecting the forward end portions of said upper and lower springs; a non-circular plate, means for connecting the rear end of the lower spring to an axle housing and simultaneously supporting said non-circular plate therebeneath; and a coil compression spring interposed between said upper spring and the non-circular plate aforesaid for augmenting the inherent resiliency obtaining between the upper and lower springs aforesaid.

3. A spring construction comprising in assembly: a semi-elliptic upper leaf spring; an eye

on the rear end thereof for mounting said spring on the chassis of an automotive vehicle; a quarter-elliptic lower leaf spring; an eye on the forward end thereof for mounting said lower spring on said chassis; an elongated plate and bolt means supporting said plate and the rear end of the lower spring beneath the axle housing of said vehicle; a centrally apertured circular plate and a headed bolt and nut assembly mounting said circular plate beneath a central portion of the upper leaf spring; a coil compression spring interposed between the free rearwardly projecting segment of the elongated plate and said circular plate, the upper and lowermost coils being welded respectively to said circular and said elongated plate; an eye on the forward end of the upper leaf spring; an eye intermediate the ends of the quarter-elliptic spring; and linkage resiliently connecting the last-named pair of eyes.

4. A spring assembly of the type described in combination with the chassis and axle housing of an automotive vehicle, said assembly including: a semi-elliptic upper leaf spring having a normally horizontal rear half section merging into a downwardly curved front half section; an eye on the end of said rear half section for mounting the upper spring on the chassis; a quarter-elliptic lower leaf spring; an eye on the forward end of the lower spring for mounting same on said chassis; an elongated plate; bolt means rigidly supporting said plate and the rear end of said lower spring beneath the axle housing; an eye on the end of said upper spring front half section, and an eye adjacent the front end of said lower spring; resiliently mounted linkage connecting the last-named pair of eyes; a centrally apertured circular plate and headed bolt and nut means mounting said plate beneath a central portion of the upper leaf spring; and a coil compression spring interposed between the circular plate and a rearwardly projecting segment of the elongated plate aforesaid.
